(57) **CLAIM**

The ornamental design for a portable recorder, as shown and described.

DESCRIPTION

FIG. 1 is a front elevational view of a portable recorder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof from a right-front view angle;

FIG. 8 is a perspective view thereof from a left-bottom view angle;

FIG. 9 is a perspective view the present portable recorder attached with a clip in use; and,

FIG. 10 is a perspective view the present portable recorder attached with a clip in an outwards status.

The broken lines are employed to show either environmental structure or unclaimed portions of the portable recorder, and form no part of the claimed design.
